INVENTOR.

W. W. Lummus.

UNITED STATES PATENT OFFICE.

WILLIAM W. LUMMUS, OF LYNN, MASSACHUSETTS.

IMPROVEMENT IN BEAMS FOR FLOORS.

Specification forming part of Letters Patent No. **139,904**, dated June 17, 1873; application filed November 19, 1872.

To all whom it may concern:

Be it known that I, WILLIAM W. LUMMUS, of Lynn, Essex county, in the State of Massachusetts, have invented certain new and useful Improvements in Iron Beams, and I hereby declare the following to be a full and exact description thereof, reference being had to the accompanying drawings forming part of this specification:

The nature or essence of my invention consists in a plate of iron with slits cut in two opposite edges, and bent to receive a wooden bar to form a nailing-surface to or at each, the bars being secured firmly to the iron by nails or otherwise; and in cutting the slits in one edge opposite the spaces between the slits in the other edge.

In the accompanying drawings, Figure 1 is an elevation of one side of a beam with my improvements. Fig. 2 is an elevation of one end, and Fig. 3 an elevation of one side and one end of a modification of said improved beam.

In the above-mentioned drawings, A is a plate of sheet metal with slits B B cut in each edge; these slits are cut about opposite the middle of the spaces between the slits on the opposite edge. That portion of the iron between the slits is bent alternately in each direction to an angle of about forty-five degrees, as shown in Fig. 2 at J J, and the edges of the portion bent off are turned up at a right angle to the part J to hold the wooden bars B and C, which are pushed in from one end, and fastened by the nails N N. The upper corner of the bar B' is cut off, as shown at E, to form a flat surface for the floor or roof-boards which may be nailed to the bar, and the lower corner of

the bar C is cut off to form a horizontal surface for the laths or ceiling which may be nailed to it.

Fig. 3 shows a modification of my improved beam. The iron between the slits is bent off at a right angle to the portion A, and the edges of the part bent off are turned up and perforated to receive the nails N N, which fasten the wooden bars B' and C to the iron. Beams, rafters, or joist, made in this way furnish a broad nailing-surface for flooring or laths.

When no nailing-strip is required at the lower edge of the beam, it may be left whole, and bent one side at a right angle to the vertical portion of the beam.

The advantages of this improved beam are its simplicity of construction and adaptation, economy in the quantity of iron used for a beam of given strength, with little danger of yielding or bending; besides, it furnishes wood nailing for flooring, roofing, ceiling, furring or laths, which nailing is partially protected from fire by the iron.

What I claim as my invention and improvement is—

1. An iron beam, consisting of a single plate of iron, with its edges slit or cut, and bent to hold nailing-strips for floor, ceiling, furring, or laths.
2. The slits in the edges of the iron beam cut or made on either edge opposite the middle of the spaces on the opposite edge, substantially as described.

WILLIAM W. LUMMUS.
